UNITED STATES PATENT OFFICE

REINHARD E. BARTELS, OF LYNN, MASSACHUSETTS; IDA M. BARTELS AND R. BUR-
LEIGH BARTELS EXECUTORS OF SAID REINHARD E. BARTELS, DECEASED

FASTENING POINT FOR SHANK STIFFENERS

Application filed November 24, 1926. Serial No. 150,559.

This invention relates to reinforcing stiffeners or shank pieces adapted to be incorporated or located in the sole portion of a shoe to strengthen and support the arch portion thereof. Shank-stiffeners of this type are customarily made of suitable sheet metal or strip steel for lightness and strength, additional strength and stiffness being secured by forming the piece with a longitudinal channel or rib. Metal stiffeners are customarily secured near their ends to the shank piece or to the sole itself by points or prongs of metal struck up from the material of the piece itself or by tacks driven through holes previously formed in the metal. It is, however, desirable in some cases to supply fastening points at intermediate positions also on the stiffener between the ends thereof. When such points are struck up from the metal of the piece itself, it tends to weaken the stiffener materially at a point where strength is most needed, that is, at the bottom of the longitudinal channel, or looking at it in an inverted manner, from the top of the rib. By my invention, I avoid this weakening of the piece at the point where the greatest stresses come and at the same time provide a simple, economical and effective way of producing a shank stiffener with sharp points of any desired length, shape and material. In carrying out my invention, I provide points or prongs at any desired places on my shank stiffeners without weakening the material thereof by securing tacks or other suitable fastening elements as by spot-welding or other equivalent means. Other advantageous features of my invention will appear from the disclosure thereof as given in the following description and on the drawings, of which,—

40 Figure 1 is a perspective view of a shank stiffener provided with one of my improved reinforcing points at each end.

Figure 2 is a similar view showing two points at each end.

45 Figure 3 is a side elevation of a stiffener showing my improved points applied at each end and at the midpoint thereof.

Figure 4 is a perspective of a metal stiffener showing at the ends thereof prongs struck up from the metal, this stiffener hav-

ing my improved points applied at positions intermediate the ends thereof.

Figure 5 is a section on the line 5—5 of Figure 3.

Figure 6 is a section on the line 6—6 of 55 Figure 4.

Figure 7 is a perspective of another type of arch-supporting shank stiffener.

Figure 8 is a sectional view of a shank 60 stiffener showing its position in the arch portion of a shoe.

Referring to the drawings in detail, 10 represents a shank stiffener preferably of steel or other metal. These stiffeners are customarily stamped from sheet metal or strip steel, but may be formed in any other desired manner. In order to give strength and stiffness to these members, they may be bent laterally to form a longitudinal rib or channel 11. In order to fit the curve of the arch 70 of the shoe, the member 10 as a whole is longitudinally bent into a corresponding curve as shown in the figures. The channel or rib 11 may be formed from a portion of the material of the piece as shown in Figure 5 or 75 may include the entire width of the stiffener as at 12 in Figure 6. These two shapes are merely illustrative of various ways of forming the longitudinal channels. Heretofore to secure the shank stiffeners in place, points or 80 prongs such as shown at 13 have been struck up from the metal to serve as fastening means, or holes have been provided through which tacks may be driven. These naturally detract from the strength of the stiffener at the 85 point where the metal is struck therefrom. Such a weakening at the ends of the piece is ordinarily not objectionable, but where fastening points are desired between the ends, that is, on the rib or channel 11, since the 90 greatest stresses come at the crown of the ridge (that is, the bottom of the channel), the removal of metal at that point weakens the structure to a serious degree and renders the stiffener liable to fracture at that point. 95 By my invention, I have discovered that the securing of small tacks 14 or other suitable pointed metal pieces to the stiffener wherever fastening points are desired takes nothing from the strength of the member, but actually 100

makes it stronger at these points. The tacks or fastening points are readily applied as by spot-welding or any other desired means of securing them, the resulting fastening points being integral with the stiffener and more suited for the purposes required than prongs struck up by the old method from the material of the reinforcing member. Another advantage inherent in my invention is that the material of the fastening points is not limited to the material of which the reinforcing member itself is made, so that if particular characteristics are desired in the material of the fastening points so as to enable them for example to be clinched readily, these characteristics may be had independently of the material which is used for the reinforcing member. According to present practice, a large proportion of the metal shank stiffeners now on the market are made of cold rolled steel, this material being sufficiently malleable to permit prongs to be struck therefrom which can be suitably clinched in the leather or fiber board into which they are driven. Many prefer stiffeners of hardened steel, however, especially for such stiffeners as that shown in Figure 7. It is not practicable to strike up prongs from such metal as the prongs are brittle and break off when an attempt is made to clinch them. By my invention, I can supply hardened steel stiffeners with malleable prongs secured integrally thereto, thus obtaining the desired characteristics for both the stiffener and the prongs. While I may use any other metal or combination of metals for the reinforcing member and for the points attached thereto, I find that certain grades of steel are very satisfactory, these being easily welded together and galvanized, enamelled, japanned, or otherwise coated, to prevent corrosion. By spot-welding tacks 14 at desired points on the stiffening member, I provide points which are integral with said member and may be varied in material and shape to suit any particular requirements. These points 14 which may comprise any suitable piece of metal having a projecting point such for example as an ordinary tack may be welded or otherwise secured to the stiffening member wherever fastening points are desired. The drawings illustrate a number of different examples of how such points may be located, but it is to be understood that I do not limit myself to any particular arrangement of the fastening points nor to any particular shape or shapes of the reinforcing member.

Having thus described certain embodiments of my invention it should be evident to those skilled in the art that various changes and modifications may be made therein without departing from its spirit or scope as defined by the appended claims.

I claim:—

1. The method of making a shank stiffener,

which comprises cutting a blank, molding said blank transversely to form a longitudinal rib, and welding a fastening point to said rib.

2. A shank stiffener having a longitudinal rib, and a fastening point welded to said rib intermediate the ends thereof.

3. A hard metal shank stiffener having an imperforate longitudinal rib extending for a portion of the length thereof, and a prong of softer metal projecting from said rib.

4. A shank stiffener comprising a longitudinally curved metal strip, said strip being laterally bent to form a longitudinal rib extending a portion of its length, and a fastening point welded to said rib intermediate the ends thereof.

In testimony whereof I have affixed my signature.

REINHARD E. BARTELS.
